UNITED STATES PATENT OFFICE.

CHARLES P. WOODBURY, OF KANSAS CITY, MISSOURI.

DESIGN FOR A SWORD HILT AND SCABBARD.

55,498.

Specification for Design. Patented June 15, 1920.

Application filed October 6, 1919. Serial No. 328,917. Term of patent 3½ years.

To all whom it may concern:

Be it known that I, CHARLES P. WOODBURY, a citizen of the United States, and a resident of Kansas City, Jackson county, State of Missouri, have invented a new, original, and ornamental Design for a Sword Hilt and Scabbard, of which the following is a specification, reference being had to the accompanying drawing, forming part thereof.

The said drawing represents a view of a sword embodying my new design.

I claim:

The ornamental design for a sword hilt and scabbard as shown.

CHARLES P. WOODBURY.
